UNITED STATES PATENT OFFICE.

CHARLES A. EVARTS, OF MERIDEN, CONNECTICUT, ASSIGNOR TO THE BRADLEY & HUBBARD MANUFACTURING COMPANY, OF SAME PLACE.

CENTRAL-DRAFT LAMP.

SPECIFICATION forming part of Letters Patent No. 430,380, dated June 17, 1890.

Application filed December 30, 1889. Serial No. 335,352. (No model.)

To all whom it may concern:

Be it known that I, CHARLES A. EVARTS, of Meriden, in the county of New Haven and State of Connecticut, have invented a new 5 Improvement in Wick-Adjusters for Central-Draft Lamps, (B;) and I do hereby declare the following, when taken in connection with accompanying drawings and the letters of reference marked thereon, to be a full, clear, and 10 exact description of the same, and which said drawings constitute part of this specification, and represent, in—

Figure 1, a side view of a wick-adjusting device, showing a section of the top of the 15 fount through which the rod passes; Fig. 2, a side view of the wick-adjuster, looking from the right of Fig. 1; Fig. 3, a transverse section on line $\alpha\alpha$ of Fig. 1; Fig. 4, a side view of the catch detached.

20 This invention relates to an improvement in wick-adjusters for central-draft lamps, and particularly to that class in which the wick is adjusted by means of a rod movable vertically through the top of the fount, the wick being 25 provided with a surrounding sleeve, with which said rod is engaged, so that the vertical movement of the rod will impart corresponding vertical movement to the wick, the object of the invention being to make a firm engagement 30 between the said rod and wick-sleeve, but yet permit its easy attachment; and it consists in the construction as hereinafter described, and particularly recited in the claim.

35 A represents the wick-sleeve, which is constructed with an annular groove B, forming two shoulders a and b , the one above the other.

In United States Patent No. 387,156, granted to me July 31, 1888, a wick-adjusting sleeve of this construction is shown, the groove of the 40 sleeve being designed for engaging the sleeve with the wick-adjuster. In that case the wick-adjusting rod is provided with a horizontal circular spring, corresponding in diameter to the diameter of the sleeve in the groove, and 45 so that by laterally turning the spring it may be forced onto the sleeve and so as to grasp it within the groove.

To simplify the construction, and yet make a firm engagement between the wick-adjusting 50 rod and the sleeve, the wick-adjusting rod C is arranged to slide through a suitable

bearing in the top D of the fount, the rod extending downward, then turned up in **U** shape, the one leg, which extends through the top of the fount, provided with a suitable 55 handle by which it may be readily operated. The other leg E is turned up parallel with the axis of the wick and carries a catch F hung upon its upper end. This catch is of segmental shape and of a width corresponding 60 substantially to the width of the groove B, and so as to lie therein, but yet so that it may be turned therefrom, as represented in broken lines, Fig. 3. The catch is constructed with a transverse slot G. (See Fig. 4.) This slot 65 terminates at one end in an enlargement H, and in the groove B is a headed stud I, (see Fig. 3,) the head of which corresponds substantially to the enlarged end H of the slot and the body of the stud to the slot G. The 70 catch F is placed upon the stud I by turning the sleeve to a position that the head may pass through the enlarged part H of the slot, and, as in broken lines, Fig. 3, then by turning the sleeve from this enlarged portion the 75 stud is carried into the slot, the head being upon the outside of the catch, as clearly seen in Figs. 2 and 3, thereby interlocking the sleeve with the catch and wick-adjusting rod and so that the up and down movement of 80 the adjusting-rod will be communicated to the wick-sleeve, the catch taking firm engagement with the sleeve between the shoulders a and b and as seen in Figs. 1 and 2. The catch terminates at its free end in an out- 85 ward projection J, to which the finger may be readily applied to turn the catch from the groove.

As in my previous patent, so in this case, when it is desired to introduce or remove 90 the wick the rod is raised so far as to bring the wick-adjusting sleeve above the top of the fount and so as to expose the engaging device. The construction of this engaging device is such as to be readily understood, 95 and simply requires a rotation of the sleeve to make disengagement between it and the catch, and then the catch turned laterally from the groove in the sleeve. The sleeve is free to be withdrawn from the fount and is 100 reset and engaged by a reverse rotation.

From the foregoing it will be understood

that I claim nothing herein shown or described in the before-mentioned Patent No. 387,156.

I am also aware of United States Patent No. 402,945, dated May 7, 1889, and claim nothing therein shown or described, the advantages 5 of my invention over these references being the avoidance of the encircling spring in the first-mentioned patent and of the locking-catch of the last-mentioned patent,

10 What I do claim as an improvement thereon is—

In a wick-adjuster for central-draft lamps the combination of the sleeve A, surrounding the wick and constructed with an annular 15 groove B, the U-shaped wick-adjusting rod

C, one leg of the rod extending through the top of the fount and guided thereby, the other leg turned up substantially parallel with the adjusting-sleeve A, a catch F upon the said second leg of said rod and corresponding to 20 said groove B in the sleeve, the catch constructed with a transverse slot G, terminating at one end in an enlarged opening, and the groove B, provided with a headed stud I, corresponding to said slot and enlarged opening, 25 substantially as described.

CHARLES A. EVARTS.
